C. E. BOWERS

HANGER DEVICE FOR ELECTRICAL OUTLET BOXES

Filed June 2, 1923

Patented Sept. 1, 1925.

1,552,204

UNITED STATES PATENT OFFICE.

CLAUDE E. BOWERS, OF LOS ANGELES, CALIFORNIA.

HANGER DEVICE FOR ELECTRICAL OUTLET BOXES.

Application filed June 2, 1923. Serial No. 643,025.

To all whom it may concern:

Be it known that I, CLAUDE E. BOWERS, a citizen of the United States, residing at Los Angeles, in the county of Los Angeles and State of California, have invented new and useful Improvements in Hanger Devices for Electrical Outlet Boxes, of which the following is a specification.

This invention has relation more specifically to an adjustable hanger for supporting in position electrical outlet boxes between ceiling joists and wall studding of buildings.

An important object of this invention is to provide an outlet box hanger that may be quickly adjusted to suit varying distances between building joists and studs to which it is secured.

A further object is to provide a hanger construction that will not interfere with the connection of wiring conduits to the outlet boxes mounted thereon.

Further objects and advantages will be apparent from the following description, reference being had to the drawings accompanying the same, in which:

Fig. 1 is a cross section of a pair of ceiling joists showing the hanger attached thereto, and the outlet box in section mounted thereon.

Fig. 2 is a plan view of the hanger secured in position on the ceiling joists, taken on line 2—2 of Fig. 1.

Fig. 3 is a view similar to Fig. 2, showing the hanger adjusted to a pair of joists spaced apart a distance less than the length of the hanger.

Fig. 4 is a cross section through an outlet box of usual form, illustrating the method of securing the same to the outlet box.

Fig. 5 is an end view of the hanger device with the outlet box in place thereon.

Fig. 6 is a similar view of the other end of the hanger device.

Fig. 7 is a perspective view of my outlet box hanger with the outlet box removed therefrom.

Strap hangers employed for mounting electrical outlet boxes to the wall studs and ceiling joists of buildings are formed of a single piece of strap iron having inturned ends for securing the same in position. Building studding and joists of two inches in thickness are usually arranged about sixteen inches on centers, forming a clear space of fourteen inches between the opposing

faces of the joists or studs, and in consequence the hangers are formed fourteen inches in length. Often the studs or joists vary in thickness, thus increasing the distances therebetween, and in such cases the workmen are required to insert a small block between one inturned end of the hanger and one face of the stud or joist to secure the hanger in position. Further, as the hanger is formed of a single straight piece of strap iron, the wiring conduits entering the side apertures of outlet boxes along the longitudinal axis of the hangers have to be bent in order to escape the inturned attaching ends of the hangers.

By means of the improved hanger described herein, the above recited difficulties relating to the installation of outlet box hangers are largely obviated, the attaching brackets of the hangers are adjustably secured thereto, rendering it a comparatively easy matter to install the same between studs or joists where the distance between the same vary. Also, by offsetting the attaching ends of the brackets to one side of the longitudinal axis of the hanger bar, no difficulty will be experienced in leading the wiring conduits into the side apertures to the boxes that are disposed in line with the hanger bar.

Referring more particularly to the drawings, 10 designates the complete hanger, consisting of a flat bar 11 formed of strap iron. Slidably mounted on the ends of bar 11, are bracket attaching members 12, and 13, formed of strap iron. Bracket 12 preferably consists of a flat portion 14 designed to engage a face of a stud or joist 15 and is secured thereto by nails, a portion 16 bent at right angles to portion 14 engages the side face 17 of the stud or joist 15, from thence it is bent outwardly as at 18, the end terminating in a substantially U-shaped bearing 19, each leg of the bearing being provided with aligned slots 20, the end of the bar 11 passing therethrough. Supporting bracket 13 is similar in form to bracket 12 and preferably consists of a flat portion 21 which engages one of the faces of stud 22, being secured thereto by nails or other securing means. Extending upwardly from one end of portion 21, and at right angles thereto, is an upwardly extending portion 23 which engages the side face of the stud 22, the upper end being offset a distance equal to the width of portion 21, and provided with

a bearing slot 24 through which one end of bar 11 passes. Each end of bar 11 is provided with a small tit 25 which is formed thereon after the brackets 12 and 13 are mounted thereon, the tits preventing disengagement of the bar from the brackets.

Slidably mounted on bar 11 is an outlet box supporting member 27, which preferably consists of a short length of pipe having aligned slots 28 in its wall, one end being exteriorly threaded. The outlet box 29 is of usual octagonal form, the side and bottom walls 30, 31, respectively, being provided with the usual "knock outs" 32, and the bottom wall 31 is also provided with a centrally disposed opening 33 through which the threaded end of member 27 passes when the outlet box is secured thereto, a washer 34 and a nut 35 securely holding the outlet box in rigid relation thereon. Secured to the threaded end of member 27, and abutting against nut 35 is a "hickey" 36, the free end thereof being interiorly threaded for the reception of the threaded end 37 of a lighting fixture, not shown.

As the free slotted ends of the bracket members are offset to one side of and parallel to the plane of attaching portions 14 and 21, wiring conduits 38 that are disposed in parallel relation to the outlet box supporting bar 11, may be led directly into the outlet box through the openings in walls 30 without bending; this feature of the invention being clearly illustrated in Figs. 5 and 6 of the drawings.

When the space between studs or joists are of less width than the standard spacing (sixteen inches on centers), one end of the bar 11 may be bent at right angles as clearly shown in Fig. 3, minor differences in the width of studs or joists occasioned mainly to uneven sizes of the same, will be provided for by the adjustable brackets without the

necessity of bending the outlet box supporting bar. After the hanger has been adjusted in position between studs or joists, the ends 19 and 24 of the brackets may be bent slightly so as to bind the ends to the bar.

From the above description it will be apparent that I have provided an outlet box hanger construction that will eliminate many difficulties experienced by workmen in the installation of outlet boxes in buildings, without materially increasing the cost of hangers, any increase in cost being compensated by the saving in the labor of installation and materials.

What I claim is:

1. A device of the class described, comprising a pair of metal supporting brackets, one end of said brackets having attaching portions, the free ends forming bearings and offset to the side of and extending parallel to the plane of said attaching portions, and a supporting bar adjustably mounted in the bearing portions of said brackets.

2. A device of the class described; comprising a pair of supporting brackets each having an attaching portion and a bearing portion, the attaching and bearing portions of each bracket being disposed in different parallel planes, and a bar adjustably mounted in the bracket bearing portions.

3. An article of manufacture comprising a pair of supporting brackets, one end of said brackets having attaching portions, the free ends forming bearings, the bearing end of one of said brackets being offset to the side of and extending parallel to the plane of its attaching portion, and a supporting bar adjustably mounted in the bearing portions of said brackets.

In witness that I claim the foregoing I have hereunto subscribed my name this 16th day of May, 1923.

CLAUDE E. BOWERS.
